(No Model.)

J. H. BULLARD.

FURNACE FOR BURNING HYDROCARBON FUEL.

No. 365,790.

Patented July 5, 1887.

UNITED STATES PATENT OFFICE.

JAMES H. BULLARD, OF SPRINGFIELD, MASSACHUSETTS.

FURNACE FOR BURNING HYDROCARBON FUEL.

SPECIFICATION forming part of Letters Patent No. 365,790, dated July 5, 1887.

Original application filed September 30, 1886, Serial No. 213,971. Divided and this application filed November 1, 1886 Serial No. 217,670. (No model.)

To all whom it may concern:

Be it known that I, JAMES H. BULLARD, a citizen of the United States, residing at Springfield, in the county of Hampden and State of Massachusetts, have invented new and useful Improvements in Air-Supplying and Pressure-Governing Devices for Hydrocarbon-Furnaces, of which the following is a specification.

This invention relates to improvements in furnaces for burning hydrocarbon fuel, and pertains particularly to improved means for supplying atomized liquid fuel and air to said furnaces and for delivering the air to the fuel-tank and from the latter to the furnace commingled with said fuel under a uniform automatically-regulated pressure; and the invention consists in the peculiar arrangement and construction of the air and fuel-supplying and regulating devices, all as hereinafter fully described, and pointed out in the claims.

In the drawing forming part of this specification are illustrated in side elevation, partly in section, a boiler and furnace, a liquid-fuel tank, and atomizers, and air-supplying and pressure-regulating devices connected therewith embodying my improvements, the side of said fuel-tank being shown partly broken away.

In the drawing, 3 indicates a steam-boiler of a well-known construction, consisting of a central tube or drum, 4, (the side thereof being shown partly broken away,) having tubes 5, connected to the sides thereof by one end and projecting laterally from said drum, a pipe, 6, being attached to the boiler to convey steam therefrom for any desired purpose. No feed-pump or pipes for supplying water to the boiler are shown in the drawing; but any well-known devices may be employed for that purpose.

A bed-plate, 7, is located under the boiler, on which the latter rests, and said bed-plate rests on short posts, as shown, which stand between the bed-plate and the top of the liquid-fuel tank 8. A furnace, 9, of metal or other suitable construction, incloses the boiler. No smoke-pipe is required for the furnace, for the reason that the combustion of the liquid fuel (which consists, preferably, of refined petroleum) under the below-described conditions

does not produce smoke to any such extent as to render a smoke-pipe necessary. The said fuel-tank is of suitable metallic construction, and has atomizing-tubes 10, attached thereto, the upper delivery ends of which are curved to bring the perforated extremity *a* thereof into such position that the atomized fuel and air will be injected through perforations *c* in the walls of the furnace, and when ignited by any suitable means will fill the latter with flame. Air to support combustion is admitted to the furnace through said perforations *c*, as well as by means below described.

The atomizers 10 consist of two tubes—an outer larger one, which is shown above the fuel-tank, on the end of which is attached a cap, as shown, through a central hole in which the fuel and air are delivered, and a smaller tube, *o*, (shown through a broken-away portion of the side of said tank,) which extends nearly to the bottom of said tank, which is partly filled with said liquid fuel *d*, always leaving an air space or chamber, *e*, between the surface of said fuel and the top of the tank. Said smaller tube *o* of the atomizer enters the lower end of the said larger tube and extends into the cap *a*, its end at that point terminating opposite the exit-hole in the cap, and an air-passage communicating with said air-chamber *e* in the fuel-tank is by the above-described tubular arrangement formed between the two tubes of the atomizer, whereby air is conducted from the chamber *e* to and through the cap *a* simultaneously with the liquid fuel, which is forced, as below described, through the inner tube, *o*. Any number of atomizers 10 may be attached to the fuel-tank proportionate to the heat required for the boiler.

An air-pipe, 12, for conveying air to the chamber *e* of the fuel-tank 8, passes through one of the upwardly-projecting ends of the latter and terminates within the opposite end of the tank, as shown, said pipe having its inner end open and perforations in its side near its opposite end, in order that it may deliver air about equally at both ends of the tank in chamber *e*.

To the end of said air-pipe 12, outside of the fuel-tank, is attached one end of a valve-
100

box, 13, having an air-passage, z , through it in line with said air-pipe, and to the opposite end of said valve-box is attached an air-pipe, 14, to which is connected, by an ordinary union-joint, 15, a pipe, 16, with which is connected an air-pump, J, by a pipe, K, and stop-valves h and 17 are connected in said pipe 16, as shown. Said air-pump may be run by any convenient power through a belt running on the pulley f thereon; or it may be operated by hand by means of the handle y , projecting from said pulley. Said pipe 16 is connected with a reservoir, 18, of compressed air, on which is an ordinary pressure gage, n , and spring escape-valve w , as shown. The aforesaid valve-box 13 has a transverse perforation through it, crossing said air-passage, in each end of which perforation is formed an ordinary stuffing-box, as shown. One end of a valve-spindle, 19, passes through said valve-box and stuffing-boxes, as shown, and across said air-passage therein, and said spindle has a transversely-perforated air-hole or valve-port, x , in that part of it within the valve-box. Said stuffing-boxes prevent the escape of air around the spindle 19, and the latter is adapted to be moved in the valve-box in a direction across said air-passage z , whereby the hole x in the spindle is brought wholly or partially into line with said passage z , thereby restricting the latter more or less when said valve-port is moved partially out of line with said passage, as shown in the drawing. On the upper end of said spindle 19 is secured a piston-head, 20, which is fitted and adapted to move in an air-cylinder, 21, thereby imparting a longitudinal or endwise motion to said valve-spindle. A spring, 22, between the lower end of said cylinder 21 and the under side of said piston-head 20, serves to move the latter upward and to bring said valve-port x of said spindle to a position, when free to do so, in a line with the passage z , as below described, thereby opening the air-passage through the valve-box, and said spring constitutes an element of resistance to the movement of the end of said spindle across said air-passage to bring the valve-port to the position shown, as pointed out hereinafter. An air-pipe, 23, connects the cylinder 21 with the air-chamber e of the fuel-tank.

The operation of the above-described air-supplying and pressure-regulating devices in connection with the fuel-tank and atomizers 55 in injecting said fuel and air into a furnace and in storing up compressed air for use in the fuel-tank when it is not convenient to run the air-pump is as follows: When the fuel-tank 8 is arranged to operate in connection 60 with a steam-boiler for running a steam-engine, the air-pump is connected with the running machinery in any suitable way, and under such conditions the valves h and 17 are open and the air pumped is sent into the pipe 16, from whence it is carried through pipe 14 and the valve-box 13 into pipe 12, and by the latter is introduced into the air-chamber e of the fuel-

tank, and any surplus of air which is pumped into pipe 16 more than may be required for the fuel-tank is carried into the reservoir 18, 70 and the air-pressure in the latter is regulated by turning the regulating-screws of the escape-valve w , the end of said screw acting on a spring in said valve, which acts against a disk therein over the outlet air-passage through 75 it. Thus under a certain air-pressure somewhat in excess of that required to operate the atomizers and to supply air to the furnace air is permitted to escape from the reservoir, so that the pressure under which the air is sent 80 by the pump J into the fuel-tank is maintained at the desired point above that required in the tank, so as to insure a constant air-supply in the latter.

The air-reservoir 18 is especially useful in 85 connection with the aforesaid fuel-tank when the air-supply therefor is dependent upon an air-pump which is only capable of being operated by the said running machinery, and where the operation of the machinery is dependent 90 upon an engine operated by steam which is generated by means of a boiler and furnace such as are herein described. Undersaid conditions a supply of air for the tank 8 and the furnace must be had to get up steam to start the engine after steam has been allowed to go down in the boiler, and said air-supply for starting the fire is provided for by storing a certain quantity of compressed air in the reservoir while the air-pump is running and by utilizing 95 said stored air for starting the fire to get up steam in the boiler, as aforesaid. After storing said air in the reservoir, the valve 17 is shut until such time as the said air is required for the purpose set forth.

An air-reservoir substantially such as is shown herein is by any suitable means supplied with such a quantity of compressed air as may be required to maintain a fire in the furnace for a certain time, and can be used in connection with said boiler and tank in many ways—as, for instance, when the boiler is used to drive an engine for propelling a street-car or other vehicle, or for propelling a boat, and for any other desirable similar purpose when it is more convenient to use a reservoir than to run a pump—and therefore the air-pressure in the reservoir must be considerably in excess of that under which it is supplied to the fuel-tank.

In practice the requisite air-pressure to be maintained in the chamber e of the fuel-tank, where the most economical consumption of fuel and favorable conditions for combustion are secured, is from one to one and one-half pound per square inch, more or less, and the air from the pump or from a reservoir is delivered at said low pressure into the fuel-tank by the governing action of the valve-spindle and its connecting devices, as follows: The power of the spring 22 to resist compression, together with the slight frictional resistance of the spindle 19 in its bearings, are adapted to be overcome by the said required degree of

air-pressure in the fuel-tank, the force of said pressure being brought to bear on the piston-head 20 through the connection of the cylinder 21 with the air-chamber *e* of the fuel-tank 5 by the pipe 23. In consequence of the latter-described action of the valve-spindle 19 the latter will, when air under pressure is flowing into the chamber *e* from a pump or reservoir, be operated by any pressure in said air-chamber in excess of said required low pressure, and said valve-port *x* will be carried more or less out of line with the air-passage *z* through the valve-box 13, thereby restricting said passage in proportion to said excessive pressure 15 in chamber *e*, and causing a uniform low pressure to be maintained in said chamber for ejecting fuel and air from the tank 8.

The above-described construction, embodying the perforated valve-stem 19, extending 20 across the compressed-air passage *z*, to serve as an air-valve, obviates any air-resistance to the proper movement of the valve.

The spring 22 may be changed at pleasure for one having more or less resisting power, in 25 order to regulate the working pressure in the fuel-tank to any other than that mentioned above.

It is obvious that the use of said fuel-tank, atomizers, and air-supplying and pressure-regulating devices need not be restricted to 30 steam-boilers, but that they may be efficiently employed for producing heat in many other relations.

This application is in part a division of my 35 application, Serial No. 213,971, filed September 30, 1886, for steam road-wagon, and of a further application, Serial No. 215,862, filed October 11, 1886, relating to hydrocarbon-furnaces for steam-boilers. The subject-matter 40 herein claimed is not claimed in the other applications referred to.

I am aware that it is not new to force a liquid fuel to a burner by air-pressure, and that air-pumps are not new and air-reservoirs 45 are not new, and that valves operated in one direction by air or steam pressure and in the other direction by a weight or spring are not new.

What I claim as my invention is—

50 1. A liquid-fuel tank having normally an air-chamber above the level of its liquid contents, fuel-atomizers attached thereto communicating with the air-chamber of the tank and also with the part of the tank devoted to liquid fuel, a reservoir adapted to contain 55 compressed air and having pipe-connection with the air-chamber of the tank, and a valve controlling the aperture in said pipe and itself controlled by a passage or pipe leading 60 from the air-chamber in the tank, all in combination, substantially as stated.

2. A boiler and furnace, substantially as described, a liquid-fuel tank having normally an air-chamber therein above the level of its 65 fluid contents, and fuel-atomizers, substantially

as described, communicating with said liquid fuel and with said air-chamber, combined with a reservoir adapted to contain compressed air, a conducting-pipe connecting said reservoir with said air-chamber having therein a valve-box, substantially as described, an air-cylinder connected with said fuel-tank chamber, a valve-spindle having one end connected to a piston-head in said cylinder and its opposite end entering said valve-box, and a spring between said piston-head and one end of said cylinder, substantially as set forth. 70

3. In combination, the fuel-tank 8, having the air-chamber *e*, the air-reservoir 18, a pipe connecting the latter and said chamber, the cylinder 21, connected by an air-pipe with the chamber *e*, the valve-box 13, connected in said pipe between the reservoir and the air-chamber, the valve-spindle 19, having one end connected to a head in said cylinder and its opposite end entering said valve-box, and a spring on said spindle within the cylinder 21, substantially as set forth. 80

4. A liquid-fuel tank, substantially as described, having normally an air-chamber 90 therein above the level of its fluid contents, and fuel-atomizers attached thereto communicating with said fluid contents and with said air-chamber, combined with an air-pump having a pipe-connection with said air-chamber, 95 and a valve, substantially as described, controlled by the air-pressure in said chamber to vary the area of the air-passage in said pipe-connection between said pump and fuel tank, substantially as set forth. 100

5. A boiler and furnace, substantially as described, a liquid-fuel tank having normally an air-chamber therein above the level of its fluid contents, and fuel-atomizers, substantially as described, communicating with said liquid 105 fuel and with said air-chamber, combined with an air-pump, a conducting-pipe connecting said pump with said air-chamber, having therein a valve-box, substantially as described, an air-cylinder connected with said fuel-tank 110 chamber, a valve-spindle having one end connected to a piston-head in said cylinder and its opposite end entering said valve-box, and a spring between said piston-head and one end of said cylinder, substantially as set forth. 115

6. In combination, the fuel-tank 8, having the air-chamber *e*, the air-pump *J*, a pipe connecting the latter and said chamber, the cylinder 21, connected by an air-pipe with the chamber *e*, the valve-box 13, connected in said 120 pipe between the pump and the air-chamber, the valve-spindle 19, having one end connected to a head in said cylinder and its opposite end entering said valve-box, and a spring on said spindle within the cylinder 21, substantially 125 as set forth.
